UNITED STATES PATENT OFFICE

2,578,004

DOOR LATCH AND LOCK

Earl W. Gifford, San Diego, Calif.

Application August 25, 1947, Serial No. 770,419

6 Claims. (Cl. 70—146)

1

My invention relates to a door latch and lock, more particularly to such a latch and lock having reciprocating handles, and the objects of my invention are:

First, to provide a door latch and lock of this class in which the handles thereof are arranged to be reciprocally operated in the direction it is desired to open the door whereby a simpler and more natural mode of operation is obtained.

Second, to provide a door latch and lock of this class having very safe and efficient dual locking means for prevention of unauthorized people from opening a door in which my door latch and lock is installed.

Third, to provide a door latch and lock of this class which is very compact and simple to install.

Fourth, to provide a door latch and lock of this class having a locking bolt therein provided with a roller engageable with a reciprocally operated cam whereby withdrawal of said bolt is very positive and requires the expenditure of a relatively small amount of force for opening said bolt from its striker.

Fifth, to provide a door latch and lock of this class which is very quiet and smooth in operation.

Sixth, to provide a door lock and latch of this class which is provided with novel bolt striker means adapted to rotate the end of the bolt into place inwardly of the striker plate.

Seventh, to provide a door lock and latch of this class having substantially cylindrical escutcheons which compensate for the installation of my door latch and lock in the doors of various thickness.

Eighth, to provide a door lock and latch of this class having a lock shaft extending through the plunger thereof from the tumbler lock on one side of the door on which my lock is installed to a control button on the other side of the door whereby said lock may be readily released from the inside of the door and readily locked from the outside by common shaft whereby extreme simplicity of operation of said lock is obtained.

Ninth, to provide a door latch and lock of this class having a novel bolt actuating spring and retracting mechanism, and

Tenth, to provide a door latch and lock of this class which is very simple and economical of construction in proportion to its utility and which will not readily deteriorate or get out of order.

With these and other objects in view, as will appear hereinafter, my invention consists of cer-

2

tain novel features of construction, combination and arrangement of parts and portions as will be hereinafter described in detail and particularly set forth in the appended claims, reference being had to the accompanying drawings and to the characters of reference thereon forming a part of this application in which: Figure 1 is a side elevational view of my door latch and lock shown in connection with a fragmentary portion 5 of a door and door jam; Figure 2 is a sectional view of my door latch and lock taken from the line 2—2 of Figure 1; Figure 3 is a fragmentary sectional view taken from the line 3—3 of Figure 2; Figure 4 is a fragmentary sectional view taken from the line 4—4 of Figure 3; Figure 5 is an enlarged fragmentary sectional view taken from the line 5—5 of Figure 2; Figure 6 is an enlarged fragmentary sectional view taken from the line 6—6 of Figure 2; Figure 7 is an enlarged fragmentary sectional view taken from the line 7—7 of Figure 2, and Figure 8 is an enlarged fragmentary sectional view taken from the line 8—8 of Figure 2.

Similar characters of reference refer to similar parts and portions throughout the several views of the drawings.

The bolt 1, spring bearing blocks 2, bolt spring 3, rollers 4 and 5, ball bearings 6, bolt casing 7, plunger casings 8 and 9, plunger supporting tubes 10 and 11, plunger 12, lock shaft 13, locking eccentric 14, locking pin 15, detent 16, escutcheons 17 and 18, casing caps 19 and 20, spacers 21 and 22, guide plate 23, snap ring 24, plunger locating plates 25 and 26, handles 27 and 28, tumbler lock 29, thumb control button 30, handle bases 31 and 32, bolt 33, striker 34, striker plate 35, cushions 36, and the plunger return spring 37 constitute the principal parts and portions of my door latch and lock.

The bolt 1 is provided with an angular cam face 1a and a straight latching face 1b in opposed relationship thereto similar to conventional door locking bolts. This bolt 1 is provided with an opening 1g therein in which the spring bearing block 2 is reciprocally mounted and engaged

by the spring 3 which tends to force said spring bearing block 2 toward the plunger 12. This bolt 1 is provided with bearing race portions 1c at opposite sides thereof in which the ball bearings 6 are engaged and maintained in contact with the inner walls of the bolt casing 7 as shown best in Figures 3 and 4 of the drawings. Thus the ball bearings 6 provide for the smooth reciprocal operation of the bolt 1 in the bolt casing 7. Rotatably mounted in fixed re-

lationship internally of the opening 1g in the bolt 1 is the roller 5 which engages one side of the plunger 12. The spring bearing block 2 carries the roller 4 rotatably mounted in connection therewith which engages the opposite side of the plunger 12 in compressed engaged relationship therewith urged by the spring 3. Thus, the spring 3 tends to extend the bolt 1 into the striker plate 35 at one side of the striker 34 which is a square in cross section member 10 pivotally mounted on a pin 34a secured in connection with the striker plate 35, all as shown best in Figure 2 of the drawings. As shown in Figure 3 of the drawings, the bolt casing 1 is provided with flange portions 1a arranged to be secured at the outer edge of the door in which my door latch and lock is installed. Secured in screw threaded relationship with opposite sides of the bolt casing 1 are the plunger casings 8 and 9. These plunger casings 8 and 9 are hollow cylindrical externally threaded casings having diametrically stepped portions 8a and 9a respectively shouldering against the outer opposite sides of the bolt casing 1, all as shown best in Figure 2 of the drawings. The plunger casing 8 is provided with an internal ledge 8b engaging the flange 10a of the plunger supporting tube 10. This plunger supporting tube 10 is externally screw threaded and rigidly connected to the handle 27. The casing cap 19 is externally screw threaded on the outer side of the plunger casing 8 and maintains the spring 37 in engaged relation with the flange 10a of the plunger supporting tube 10 which spring 37 tends to force the handle 27 together with the plunger supporting tube inwardly toward the bolt 1, the force of the spring 37 being resisted by the flange 10a resting on the shoulder 8b of the plunger supporting tube 10 and plunger casing 8 respectively. Engaging the inner end of the casing cap 19 is a spacer 21 which is a helical coil of flat wire designed to prevent movement of the plunger casing 8 within the inlettet portion of the door in which my door latch and lock is mounted. The escutcheon 17 is a hollow cylindrical escutcheon adapted to be used in connection with doors of various thickness which overlaps the casing cap 19 and covers the spacer 21 providing a neat appearance of my door latch and lock when installed in connection with doors of various thickness. The plunger casing 9 is screw threaded in the side wall of the bolt casing 1 as herebefore described, and is provided with an internal shoulder 9b engaged by the guide plate 23 held in place by the snap ring 24. This guide plate 23 is provided with an opening 23a therein through which the plunger 12 extends, as shown best in Figures 2 and 5 of the drawings. Externally screw threaded on the outer end of the plunger casing 9 is the casing cap 20 which engages the spacer 22 similar to the spacer 21 hereinbefore described surrounded by the escutcheon 18 similar to the hereinbefore described escutcheon 17. The plunger supporting tube 11 is externally screw threaded internally of the handle 28 and is substantially shorter than the plunger supporting tube 10 permitting inward movement thereof into the plunger casing 9. The plunger locating plates 25 and 26 are similar in construction and are substantially U-shaped as shown in Figure 6 of the drawings engaging annular grooves 12a and 12b respectively in opposite ends of the plunger 12. These plunger locating plates 25 and 26 are internally shouldered in the

plunger supporting tubes 10 and 11 and serve to support the plunger 12 in these tubes 10 and 11 during their reciprocal movement in the plunger casings 8 and 9 through the bolt casing 1. The plunger 12 is provided with an inclined cam surface 12c on its one side engageable with the roller 5 for retracting the bolt 1 from the striker 34. The opposite side 12d of this plunger 12 is straight and provides a constant bearing surface on which the roller 4 is engaged whereby a constant abutment for the spring 3 is provided. The plunger 12 is provided with a bore 12e extending centrally therethrough in which the lock shaft 13 is rotatably mounted. On one end of this shaft 13 is provided an engaging lever 13a having a projection 13b engaged by the eccentric pin 29a of the conventional tumbler lock 29. Extending through this shaft 13 near its opposite end is a pin 13c engaging a washer 13d in the recess 27a of the handle 27 which locates the shaft 13 longitudinally of the plunger 12. The inner end of the shaft 13 is fitted with a thumb control button 30 located in a recess 27b in the handle 27, providing manual control for rotation of the shaft 13 inwardly of the door in which my door latch and lock is installed. The shaft 13 is provided with a spur gear portion 13e meshing with gear teeth 15a on the pin 15. The teeth 15a on the pin 15 form a rack which permits rotation of the shaft 13 to reciprocate said pin 15 vertically in the plunger 12 causing said pin 15 to be extended into a recess portion 1d in the bolt 1, as shown best in Figure 8 of the drawings. Adjacent the spur gear portion 13e of the shaft 13 is the eccentric lock 14 secured on said shaft 13 extendible into interfering relationship with the inlettet opening 23a in the guide plate 23, thus preventing reciprocal movement of the plunger 12 toward the inner side of the door in which my door latch and lock is inlettet. The spring loaded detent 16 engages recess portion 14a in the eccentric lock 14 when in certain positions for holding the same in such positions, all as shown best in Figures 2 and 5 of the drawings. It will be here noted that the plunger 12 is provided with an opening 12f therein adjacent the inclined cam portion 12c in which said eccentric lock 14 is positioned. The handles 27 and 28 are mounted in connection with the handle bases 31 and 32 respectively by means of pins 31a and 32a respectively. It will be noted that the axis of the pins 31a and 32a are a sufficient distance from the axis of the plunger 12 so that slight tolerance is required between the plunger supporting tubes 10 and 11, plunger 12 and the casing caps 19 and 20. It will be obvious that the plunger supporting tubes 10 and 11 travel in a slightly arcuate path during reciprocal movement of the plunger 12 for a short distance sufficient to retract the bolt 1 from the striker 34 for opening the door to which my door latch and lock is secured.

The operation of my door latch and lock is substantially as follows: When a person at the outside of the door desires to open the same, he presses inwardly on the handle 28 which pivots on the pin 32a. With the inward-pivotal movement of the handle 28, the plunger supporting tube 11 is forced inwardly of the plunger casing 9 and the inclined surface 12c engaging the roller 5 forces the same laterally of the plunger 12 causing retraction of the bolt 1 which compresses the spring 3 and maintains the rollers 4 and 5 in

positive engaged relationship with opposite sides of the plunger 12. When the door is again closed, the spring 37 returns the plunger 12 to its original position as shown in Figure 2 of the drawings, and the flange 10a of the plunger supporting tube 10 engages the shelf 8b of the plunger casing 8 positively indexing the plunger 12 relatively to the roller 5 so that maximum extension of the bolt 1 is accomplished in order to properly engage the same with the striker 34. It will be noted that as the bolt 1 at its base 1a passes the striker 34, the striker 34 rotates on the pin 34a reducing considerably the friction in the closing of the bolt 1 relatively to the striker plate 35. When it is desired to lock the door from the outside, a key is inserted in the tumbler lock 29 and the pin 29a thereof is rotated carrying the plate 13a and engaging the same at its extension 13b which rotates the shaft 13 disposing the eccentric 14 in interfering relation with one side of the guide plate 23, and rotation of the shaft 13 also actuates the spur gear portion 13e of said shaft 13 in its meshed relationship with the rack teeth 15a of the pin 15 which causes said pin 15 to be extended into the recess 1d of the bolt 1. Thus a dual locking arrangement of my door latch and lock is provided which renders the same very safe and secure from lock pickers or unauthorized persons. The shaft 13 may be rotated to the unlocked position by means of the thumb control knob 30 at the inner side of the door as desired.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a door latch of the class described, the combination of a bolt casing, a bolt reciprocally mounted therein having an opening therethrough, a spring bearing block in said opening, a spring engaging said bolt and tending to force said spring bearing block toward one end of said bolt, a plunger extending through said opening in said bolt intermediate said spring bearing block and the opposite end of said bolt, said plunger provided with cam means arranged to retract said bolt into said casing, a roller on said spring bearing block engageable by one side of said plunger, and a second roller rigidly connected to said bolt engageable with said cam means on said plunger, a tumbler lock at one end of said plunger, a shaft operatively connected with said tumbler lock extending through said plunger and having a geared portion thereon, a pin having a rack portion in mesh with said gear portion extending through said plunger, said bolt provided with a recess adapted to receive said pin.

2. In a door latch of the class described, the combination of a bolt casing, a bolt reciprocally mounted therein having an opening therethrough, a spring bearing block in said opening, a spring engaging said bolt and tending to force said spring bearing block toward one end of said bolt, a plunger extending through said opening in said bolt intermediate said spring bearing block and the opposite end of said bolt, said plunger provided with cam means arranged to

retract said bolt into said casing, a roller on said spring bearing block engageable by one side of said plunger, and a second roller rigidly connected to said bolt engageable with said cam means on said plunger, a tumbler lock at one end of said plunger, a shaft operatively connected with said tumbler lock extending through said plunger and having a geared portion thereon, a pin having a rack portion in mesh with said gear portion extending through said plunger, said bolt provided with a recess adapted to receive said pin, a guide plate through which the cam portion of said plunger extends, and an eccentric lock on said shaft extendible into interfering relationship with said guide plate.

3. In a door latch and lock of the class described, the combination of a pair of pivoted handles arranged to be positioned on opposed sides of a door, a plunger interconnecting said handle then extending through said door, and having an inclined cam portion thereon, a bolt having a roller engaging the cam portion of said plunger, a second roller being spring loaded and mounted within said bolt and engaging the opposite side of said plunger from said first-mentioned roller, a tumbler lock in connection with one of said handles, the shaft extending therefrom, a pin laterally reciprocal in said plunger operatively engageable with said shaft, said bolt provided with a recess engageable by said pin when said shaft is rotated.

4. In a door latch and lock of the class described, the combination of a pair of pivoted handles arranged to be positioned on opposed sides of a door, a plunger interconnecting said handle then extending through said door, and having an inclined cam portion thereon, a bolt having a roller engaging the cam portion of said plunger, a second roller being spring loaded and mounted within said bolt and engaging the opposite side of said plunger from said first-mentioned roller, a tumbler lock in connection with one of said handles, the shaft extending therefrom, a pin laterally reciprocal in said plunger operatively engageable with said shaft, said bolt provided with a recess engageable by said pin when said shaft is rotated, said handles pivoted on a vertical axis.

5. In a door latch and lock of the class described, the combination of a pair of pivoted handles arranged to be positioned on opposed sides of a door, a plunger interconnecting said handle then extending through said door, and having an inclined cam portion thereon, a bolt having a roller engaging the cam portion of said plunger, a second roller being spring loaded and mounted within said bolt and engaging the opposite side of said plunger from said first-mentioned roller, a tumbler lock in connection with one of said handles, the shaft extending therefrom, a pin laterally reciprocal in said plunger operatively engageable with said shaft, said bolt provided with a recess engageable by said pin when said shaft is rotated, the opposite end of said shaft from said tumbler lock having a manual control knob in connection therewith for manually operating said shaft inwardly of said door.

6. In a door latch and lock of the class described, the combination of a pair of pivoted handles arranged to be positioned on opposed sides of a door, a plunger interconnecting said handle then extending through said door, and having an inclined cam portion thereon, a bolt having a roller engaging the cam portion of said

plunger, a second roller being spring loaded and mounted within said bolt and engaging the opposite side of said plunger from said first-mentioned roller, a tumbler lock in connection with one of said handles, the shaft extending therefrom, a pin laterally reciprocal in said plunger operatively engageable with said shaft, said bolt provided with a recess engageable by said pin when said shaft is rotated, the opposite end of said shaft from said tumbler lock having a 10 manual control knob in connection therewith, for manually operating said shaft inwardly of said door, a guide plate for said plunger, said shaft having an eccentric portion arranged to interfere with said guide plate when said shaft is 15 rotated.
